[57] CLAIM

The ornamental design for a cable coring tool, substantially as shown and described.

DESCRIPTION

FIG. 1 is a front elevational view of a cable coring tool of my new design;

FIG. 2 is a rear elevational view of the cable coring tool shown in FIG. 1;

FIG. 3 is a side view of the cable coring tool shown in FIG. 1, looking from the left edge of the drawing in FIG. 1;

FIG. 4 is a side view of the cable coring tool shown in FIG. 1, looking from the right edge of the drawing in FIG. 1;

FIG. 5 is a top view of the cable coring tool shown in FIG. 1;

FIG. 6 is a bottom view of the cable coring tool shown in FIG. 1;

FIG. 7 is a sectional view taken along the line 7—7 of FIG. 1.
